TAIL LIGHT

Peter E. Brady, Willowdale, Ontario, Canada, assignor to
Dominion Auto Accessories Limited, Toronto, Ontario,
Canada

Filed Aug. 9, 1973, Ser. No. 387,203

Term of patent 14 years

Int. Cl. D26—06

U.S. Cl. D48—32 R

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a top perspective view of the tail light showing my new design.

FIG. 2 is a bottom perspective view thereof.

FIG. 3 is a front elevational view thereof.

FIG. 4 is a top plan view thereof.

FIG. 5 is a side elevational view thereof.

FIG. 6 is a top perspective view of a modified form of the tail light.

FIG. 7 is a bottom perspective view thereof.

FIG. 8 is an elevational view thereof.

FIG. 9 is a top plan view thereof.

FIG. 10 is a side elevational view thereof.

FIG. 11 is a rear elevational view of the tail light shown in FIGS. 1-10.

FIG. 12 is a bottom plan view of the tail light shown in FIGS. 1-10.

The faceting is partially shown on the front and sides of the light lens for convenience of illustration, it being understood that the faceting is uniformly continuous over the areas indicated.

I claim:

The ornamental design for a tail light, as shown and described.
